DINSMORE AUSTIN, OF UNDERHILL, VERMONT.

Letters Patent No. 74,274 dated February 11, 1868.

IMPROVEMENT IN WHIFFLE-TREE TUG.

The Schedule referred to in these Letters Patent, and making part of the same.

TO ALL WHOM IT MAY CONCERN:

Be it known that I, DINSMORE AUSTIN, of Underhill, in the county of Chittenden, and in the State of Vermont, have invented certain new and useful Improvements in Whiffle-Tree Tug; and do hereby declare that the following is a full, clear, and exact description thereof, reference being had to the accompanying drawings, and the letters of reference marked thereon.

In the annexed drawings, making a part of this specification, A represents a part of a swingle-tree, with the side of one end cut away, to show the construction and position of the parts. The swingle-tree A is provided with the pin or tug a, inserted into and extending from the centre of either end, and the hollow arm D, which is made so as to form a ferrule around the end of the swingle-tree, which has also a groove or mortise in the end for one of the prongs of the lever B to work or play in. The arm D is provided with a shoulder, x, to which is attached a coiled or other spring, f, for the purpose of holding the lever B in place. B represents a lever, having two prongs or hooks, b b, pivoted to the arm D, and provided with a shoulder, against which the spring f presses, and thereby keeps the lever and prongs in position. By pressing on the outer extremity of the lever B, or by pulling on the cord or string C, which is attached to the outer extremity of said lever, and run through a pulley or staple, e, and thence into a carriage, or wherever desired, the prongs b b are thrown out of the groove or mortise, and thereby slip the trace R off from the pin a, and thus unfasten the horse or other animal from the carriage without moving from the seat thereof, simply by pulling on a cord, C.

Disastrous accidents of the gravest character may be readily prevented by this simple and convenient device.

When it may be desired to hitch up an animal, it is done by simply pressing on the outer end of the lever B, and bringing the prongs b b out so that the trace R can be slipped between them, and then on to the pin a, where it is securely held by the prongs b b, by means of the spring f and the lever B.

Having thus fully described my invention, what I claim as new, and desire to secure by Letters Patent, is—

1. The lever B, pivoted to an arm, D, attached to the end of a swingle-tree, and provided with two prongs or hooks, b b, constructed substantially as and for the purposes specified.
2. The combination of the two-pronged lever B with the hollow arm D, the spring f, and swingle-tree A, when used as and for the purpose set forth.

In testimony that I claim the foregoing, I have hereunto set my hand, this 7th day of December, 1867.

DINSMORE AUSTIN.
